ABSTRACT

In the hydrogenation of residue-containing hydrocarbon oils, coke formation is suppressed by predissolving hydrogen in the oil at a temperature below 700° F. and carrying out the hydrogenation at a temperature above 700° F.

6 Claims, No Drawings

**HYDRODESULFURIZATION OF HEAVY
HYDROCARBON OIL WITH HYDROGEN
PRESATURATION**

This invention relates to the hydrogenation of heavy hydrocarbon oils. More particularly, it is concerned with the desulfurization of hydrocarbon oils containing at least 1 percent Conradson Carbon Residue.

Reactions involving the catalytic hydrogenation of light hydrocarbon oils are known and have been carried out frequently both experimentally and commercially. Although recently there has been considerable discussion regarding the removal of sulfur from heavy hydrocarbon fuels, installations for the practice of the catalytic hydrodesulfurization of heavy petroleum oils, although greatly desirable, have not received much commercial acceptance because of the rapid deactivation rate of the catalyst. The commercial catalytic hydrodesulfurization of light hydrocarbon oils such as naphthas has been practiced successfully for many years. This is so because the catalyst requires regeneration for the restoration of catalytic activity as infrequently as once every 12 or 15 months. Ordinarily the catalyst is regenerated by removing the coke deposited thereon by a procedure which involves sweeping the reactor with an inert gas and then introducing into the catalytic reaction zone a gaseous mixture containing a relatively small amount of oxygen to prevent overheating of the catalyst bed by the exothermic oxidation of the coke or carbon on the catalyst. Gradually, the oxygen content of the gas is increased while maintaining the temperature of the catalyst bed within the desired limits until essentially all of the coke or carbon has been removed as carbon dioxide. The reactor is then swept with an inert gas and the on-stream period is resumed.

Unfortunately, in the catalytic hydrogenation of heavy residue-containing hydrocarbon oils not only is the catalyst rapidly deactivated by the deposition of coke thereon but, in addition, metals, such as nickel, vanadium and iron which also have a detrimental effect on its activity are deposited on the catalyst.

The particular problem involved in the desulfurization or hydrogenation of heavy hydrocarbon oils is that not only is the catalyst deactivated rapidly by the deposition of coke thereon necessitating frequent regeneration but the regeneration of the catalyst by oxidation of the coke does not remove the deposited metals. Thus, not only does the catalyst become deactivated rapidly but, in addition, the ordinary type of oxidative regeneration does not restore the catalyst to a commercially practical activity.

In the hydrogenation of residual stocks the major part of the hydrocarbon is in the liquid phase at the temperature and pressure of the reaction zone when conventional operating conditions are used. This liquid phase hydrocarbon exists as a film over the catalyst particles in down-flow operations. In order for the hydrogenation reaction to take place, hydrogen must first dissolve in the liquid from the gas phase and then diffuse through the liquid film to the catalyst surface before catalytic hydrogenation can begin. It follows that if the rate of the hydrogen reaction is greater than the rate of hydrogen solution or diffusion, the reaction site at the point of contact between the catalyst and the oil will be hydrogen deficient and consequently reactions other than hydrogenation, such as cracking, which lead to the deposition of coke and the concomitant deactivation of the catalyst will take place. However, if an amount of hydrogen at least equivalent to that required in the hydrogenation reaction can be predissolved in the liquid to provide a sufficient supply of hydrogen at the reaction site, undesired side reactions would be suppressed and the desired hydrogenation would be promoted.

According to our invention there is provided a process for the catalytic hydrogenation of heavy hydrocarbon oils containing at least 1 percent Conradson Carbon Residue which comprises passing said oil in intimate contact with hydrogen through a presaturation zone at a temperature below 700° F. and then contacting the liquid oil containing dissolved hydrogen with a hydrogenation catalyst in the presence of free hydrogen under hydrogenating conditions at a temperature above 700° F.

The charge stocks to which the process of the present invention may be applied include any hydrocarbon oil having a Conradson Carbon Residue of at least 1 percent for example at least 5 percent or even 10 percent or higher such as atmospheric residua, vacuum residua, heavy gas oils, shale oil, tar sand oil, crude petroleum oils, and the like. The charge stock is introduced into a presaturation zone where it is contacted with hydrogen under conditions to effect the solution of a substantial amount of hydrogen in the oil. In this respect, the term "presaturation" is intended to mean presolution, such as occurs with the solution of a solute in a solvent as distinguished from chemical saturation where an unsaturated compound is hydrogenated to produce a chemically saturated compound. To effect the presaturation, the oil is brought into intimate contact with about 500-10,000 SCF hydrogen per barrel of oil at an elevated pressure such as 500-5,000 p.s.i.g. and a temperature below 700° F. preferably between 500° F. and 700° F. This is done preferably by passing the oil and hydrogen over a bed of inert contact material whereby a large surface area of oil is exposed to contact with hydrogen. Advantageously, the pressure is the same as that of the hydrogenation zone. Although the prior art shows that hydrogen becomes increasingly soluble in hydrocarbons as the temperature is increased, it has been found unexpectedly that for the purpose of the present invention the temperature of the presaturation zone should be maintained below 700° F. although more hydrogen would be dissolved in the oil at higher temperatures. Suitably the contacting is carried out in the presence of a catalytically inert material which has a large surface area. Such materials include ceramic packing material whose chief chemical constituent is alpha alumina containing minor amounts of silica. Various grades of alumina ranging from the high surface area gamma type catalyst support grades to the relatively low surface area alpha forms. Preferred packing is in the shape of Berl saddles or Raschig rings.

The oil containing dissolved hydrogen is then brought into contact with a hydrogenation catalyst at a pressure between 500-5000 p.s.i.g., a temperature between 700° and 900° F., a space velocity between 0.1 and 10 volumes of oil per volume of catalyst per hour in the presence of between 500 and 20,000 standard cubic feet of free (as distinguished from dissolved) hydrogen per barrel of oil. Preferred conditions are temperatures between 700° and 850° F. pressures between 1,000 and 2,000 p.s.i.g., space velocities between 0.25 and 1.5 and hydrogen rates between 600 and 10,000 standard cubic feet per barrel. Advantageously, the volume ratio of the presaturation zone to the hydrogenation zone is within the range of 5:1 to 1:1 preferably about 2:1.

The presaturation and hydrogenation zones may be in separate reactor vessels or within the same reactor vessel. It is also possible to carry out the presaturation by passing the oil upflow or downflow through the inert bed with the hydrogen flow either cocurrent with or countercurrent to the oil flow. Similarly, the flow of oil through the hydrogenation zone may be either upflow or downflow with cocurrent or countercurrent hydrogen flow.

In a preferred embodiment of the present invention the beds are contained within the same reactor vessel and the oil is introduced at the top of the vessel and is passed downflow first through the presaturation zone containing a bed of Berl saddles and then downflow through the catalytic hydrogenation zone. Hydrogen is introduced at the bottom of the catalyst bed and also at the bottom of the presaturation zone to flow upward countercurrently to the oil.

The catalyst used in the hydrogenation zone comprises a hydrogenating component impregnated on a substantially inert support, such as silica, alumina, magnesia or zirconia and mixtures thereof. The hydrogenating component may be a Group 8 metal or compound thereof, optionally used in conjunction with a Group 6 metal or compound thereof. Preferably, the Group 8 metal is present in the catalyst in an amount between about 2 and 15 percent by weight of the catalyst composite and the Group 6 metal, if used, is present in an amount between about 5 and 30 percent. Preferred com-

binations are catalysts comprising 4- 8% nickel or cobalt and 15-30 percent molybdenum or tungsten in either oxide or sulfide form supported on alumina.

The hydrogen used in the process of our invention need not necessarily be pure. Hydrogen having a purity of at least 65 volume percent may be used although hydrogen having a purity of at least 75 percent is preferred. Suitable sources of hydrogen are catalytic reformer by-product hydrogen, electrolytic hydrogen or hydrogen produced by the partial oxidation of carbonaceous material followed by shift conversion and CO_2 removal.

The following examples are given for illustrative purposes only.

EXAMPLE I

In this example the charge is an Arabian vacuum residuum having the following characteristics:

API Gravity	8.7
Sulfur, wt. %	3.4
Nitrogen, wt. %	0.28
Conradson Carbon Residue, wt. %	17.55
Metals (Ni, V, Fe) ppm	17, 41, 25

The apparatus in this example is a contact zone divided into two sections, an upper section containing inert packing in the form of one-quarter inch Berl saddles and a lower section containing a bed of hydrodesulfurization catalyst prepared to contain 3.3 percent nickel oxide and 15.8 percent molybdena supported on alumina, the upper to lower section volume ratio being 2:1. The hydrocarbon charge is introduced at the top of the apparatus to flow downwardly through the inert packing and then through the catalyst bed. Hydrogen is introduced at the bottom of the apparatus and also at the bottom of the inert packing to flow upwardly countercurrent to the downflowing charge.

Operating and other data appear below.

TABLE I

Time on stream hours	24	72	120
Pressure, psig	1,500	1,500	1,500
Hydrogen rates, SCFB			
to catalyst	10,000	9,300	8,250
to packing	870	800	750
Temperature °F.			
Top	748	749	749
Intermediate	748	750	747
Bottom	748	750	748
*Space velocity, w/w/hr	0.7	0.73	0.8
Liquid Product, wt % charge	104.2	108.9	112.3
Sulfur, wt. %	2.1	2.3	2.6
% desulfurization	47.5	42.5	35.0

*basis catalyst

These data show that the desulfurization activity of the catalyst decreases on the average 12.5% per 100 hours on-stream.

EXAMPLE II

This example is substantially a repeat of Example I with the exception that the temperature of the upper section containing the inert packing of Berl saddles is maintained below 700° F. The "middle" temperature recorded below is registered near the bottom of the inert packing.

TABLE 2

10	Time on stream, hours	12	60	156
	Pressure, psig	1,500	1,500	1,500
	Hydrogen rates, SCFB			
	to catalyst	9,250	10,000	10,000
	to inert packing	750	870	820
	Temperature °F.			
15	Top	602	603	603
	Middle	603	675	680
	Bottom	748	748	752
	Space velocity w/w/hr	0.69	0.69	0.71
	Liquid Product wt. % charge	101.0	106.6	109.7
	Sulfur wt%	2.0	2.1	2.2
20	% Desulfurization	50.0	47.5	45.0

The above data show that when the presaturation temperature is maintained below 700° F. not only is the initial desulfurization activity of the catalyst higher, but in addition, its deactivation rate is lower, in the case of Example II being 3.5 percent per 100 hours compared with 12.5 percent per 100 hours in Example I.

The present invention is also superior to prior art processes in that in known processes as the hydrogenation temperature of heavy oils increases so does the deactivation rate whereas, with our process, as the hydrogenation temperature is increased, there is a minimal increase in the catalyst deactivation rate with considerably improved desulfurization.

Other modifications and variations of the invention as hereinbefore set forth may be made without departing from the spirit and scope thereof, and therefore, only such limitations should be imposed as are indicated in the appended claims.

I claim:

1. A process for the catalytic hydrodesulfurization of a heavy hydrocarbon oil containing at least 1 percent Conradson Carbon Residue which comprises passing said hydrocarbon oil in intimate contact with hydrogen through a presaturation zone at a temperature between 500° F. and 700° F. and then contacting the oil substantially saturated with hydrogen with a hydrodesulfurization catalyst under desulfurization conditions and at a temperature above 700° F. and below 900° F.
2. The process of claim 1 in which the presaturation zone contains an inert packing.
3. The process of claim 2 in which the inert packing comprises alumina.
4. The process of claim 1 in which the pressure of the presaturation and desulfurization zones is between 500 and 5,000 p.s.i.g.
5. The process of claim 1 in which the heavy hydrocarbon oil is a residue-containing petroleum oil.
6. The process of claim 5 in which the heavy hydrocarbon oil contains at least 5 percent Conradson Carbon Residue.
